UNITED STATES PATENT OFFICE.

JAMES LORENZO GAGE, OF CHICAGO, ILLINOIS, ASSIGNOR OF ONE-HALF
TO NATHAN MEARS, OF SAME PLACE.

WOOD-CUTTING MACHINE.

SPECIFICATION forming part of Letters Patent No. 272,038, dated February 13, 1883.

Application filed August 7, 1882. (No model.)

To all whom it may concern:

Be it known that I, JAMES LORENZO GAGE, of the city of Chicago, Cook county, in the State of Illinois, being a subject of Great Britain, have invented a new and useful Improvement 5 in Wood-Cutting Machines, of which the following is a specification.

My invention consists in providing a revolving head, having knives placed on the face, with 10 a compressing device to prevent the wood from checking. This gives a shear cut, which I consider the best for cutting when it can be obtained. Second, combining with said wheel a carriage having an intermittent feed. I attain 15 these objects by the mechanism illustrated in the accompanying drawings, in which—

Figure 1 is a front elevation. Fig. 2 is a top view. Fig. 3 is a vertical section through 3 3, Fig. 2. Fig. 4 is a section of wheel A through 20 4 4, Fig. 1, showing the position of the bar as to the cutting-edge of the knife. Fig. 5 is an enlarged perspective view of the carriage and means for holding the same against the back-thrust.

25 Similar letters refer to similar parts in the several views.

A is a large wheel, having two knives, e, placed on its face on opposite sides, as shown in Fig. 1, and having recesses cast out, commencing at the edge of the knife, as shown in Fig. 4, for the material to pass out as it is being cut from the block.

B is a suitable frame, which carries the several parts of the machine.

30 C is the main shaft, that carries the wheel A. This shaft gives motion also to the several acting parts. On the front of shaft C a spur-wheel, a, is keyed that meshes into a spur-wheel of equal size on shaft f, and communicates motion to shaft h by means of inter-wheels K. On the shaft h there are two cams, m, Fig. 3, set on opposite sides. These cams give a reciprocating motion to racks n by means of yokes o. These racks n engage (when the 40 machine is operating) with racks on the bottom of carriage P, Figs. 1, 2, and 3, and as they reciprocate give a zigzag motion to the carriage. These racks n rest on the springs R, which rest on bars S, that are attached to

main frame B, and are given a vertical motion 50 by cams x on shaft x' by means of treadle y. To the main frame B, on the upper side and in front of wheel A, are bolted two racks, B', having a recess formed on their under sides, as shown at a', Fig. 1. These recesses admit 55 the slides formed on the ends of carriage P, and keep it in its place. The racks B' are engaged by pawls e, attached to carriage P. On the inner ends of the pawls are right and left screws 6, upon which are arranged the nuts y'. 60 These nuts have their inner ends received in holes formed through the side bars, 8, of a handle, 2. The nuts are adapted to slide in said side bars of the handle, and are thrown outwardly and apart, so as to hold the pawls in 65 engagement with racks B', by means of an expansion-spring, g, arranged in any suitable way between the inner ends of the screws which pass through the nuts, as shown in Fig. 5. The spring yields while the carriage is moved forward and the pawls pass from tooth to tooth; but when the carriage is to be moved back the pawls can be positively drawn toward 70 each other and held in disengagement from the racks by turning down the handle, which 75 in turning the nuts causes the screws to move inwardly, or toward each other.

The carriage has suitable dogs, 3, for holding the block operated by handle 4. This handle will connect with devices for drawing the 80 dogs toward each other or moving them apart; but as such mechanism is found in nearly all machines of this class it need not be further illustrated or described. The racks n and B' have their teeth the same size as on the bottom of the carriage. Below the cutting-edge of the knife e a bar, 5, is placed, having on the side next the knife a longitudinal rib or projection, 10, rounded or made semicircular in cross-section, which said projection strikes the 85 wood in advance of the knife and compresses it so that the pores are closed and the knife passes through solid fiber and prevents any checks that would otherwise be produced. This bar is placed longitudinally in respect to the 90 knife and on an angle thereto for cutting tapering material. A roller may be substituted, but I prefer the bar.

The operation of this machine is as follows: The wheel being set in motion, the operator presses on the lever *y*, which throws the racks *n* into gear with the racks on the bottom of 5 the carriage, and these racks, being moved end- wise by means of cams *m*, force one end of the carriage at a time forward the distance of the pitch of the tooth. The other cam coming around moves the other end an equal distance. 10 While one cam is in contact with the point or rear part of the yoke the other is disengaged while passing around. This allows the carriage to remain fixed while the knife is cutting through the block, the several gears and 15 cams first being set so that the forward movement of the carriage is performed between the two knives. At each forward movement of the carriage the pawls *e* move one tooth in racks *B'* and hold the carriage rigid while 20 the knife is cutting and the bar is pressing against the block. Otherwise the compression would be lost and checks produced. While the wheel passes around, rounded rib or projection of the bar, striking in advance of the 25 knife, compresses the wood between itself and the carriage, thereby producing sound material. A shear cut can be given to a reciprocating knife by elevating one end of the knife above the other. This I consider an equivalent cut when compressing devices are attached. 30

It will be seen that the spring *g* tends to throw the pawls *e* out, so that they shall engage the racks. When the pawl passes from 35 one tooth to another the spring yields to such pressure, and at the same time holds the opposite pawl firmly in engagement with its appropriate rack, the nut on the screw, which is thus pushed inwardly by the pawl passing over the 40 rack-teeth, sliding slightly in such case through the handle-arm in which it is fitted. When the opposite pawl is moved along the rack by the movement of the carriage at its end carrying said pawl, a similar operation takes place, 45 said second pawl moving over its rack and the remaining pawl engaging its rack by reason of the spring. When the handle is operated so as to turn the nuts and force them outwardly against projections 11 on the carriage, 50 the screws will be moved inwardly, thus freeing both pawls from their respective racks and allowing the carriage to be moved back. By drawing the handle 2 down the pawls are disengaged from racks *B'*, and by displacing racks 55 *n* by treadle *y* from the racks under the carriage, the carriage can be drawn back.

In conclusion, I will state that in this machine the bar is set an angle to the knife, so as to cut a shingle with the required taper. In 60 cutting shingles the presser-bar maintains an even pressure throughout the operation. This result is obtained for the reason that one end of the carriage being moved up first, one end of the block from which the shingles are cut 65 is placed ahead of the other, whereby the butt-end of the shingle is cut from said advanced

end, and the front face of the block, while at an angle to the knife, is parallel with the presser-bar. In this way, then, the bar presses equally the entire length and depth of the 70 block, while the knife cuts down through the block in a vertical plane. After the cut has been made the other end of the carriage is moved ahead, so that the presser-bar belonging to the next knife will, during the further 75 revolution of the wheel, be brought parallel with the face of the block, while the next knife will be at an angle thereto, so as to cut the shingle with its proper taper. The block has been moved ahead at one end the thickness of 80 the butt of a shingle preparatory to cutting such second shingle, which latter is cut into the shape of the space between the bar and the knife. It will be found in practice that there will be no choking of the material between the bar and the knife, since the edge of the knife is set slightly above the top of the presser-bar, and as the outer end of the knife passes down through the bottom of the block first, so that when the cut is entirely made the 90 shingle will have passed through the throat of the wheel, except a small corner of the shingle, which will in practice pass through the throat of the wheel without difficulty. 95

In cutting shingles with my improved machine, the shingles, if of ordinary width, will not be appreciably thinner at one side edge than at the other side edge. I may also observe that the wood, being steamed, yields to the pressure of the presser-bar, and this yielding of the block aids in maintaining a continuous pressure in cutting a shingle, since the wood which yields to pressure has a tendency to expand against the presser-bar during the operation of severing a shingle. If the bar and 100 knife were parallel and the block fed straight forward, it will be obvious that pieces of equal thickness would be cut by the rotary cutter. As it is, however, the bar set at an angle and the zigzag movement of the carriage serve to 105 produce a shingle. 110

What I claim, and desire to secure by Letters Patent, is—

1. In a wood-cutting machine, a revolving head, with the knives placed on the face side, 115 as shown and described, in combination with a presser-bar having a longitudinal projection on its front side, and a carriage having an intermittent feed, for the purpose set forth.

2. In a wood-cutting machine, the revolving wheel *A*, provided with knives, and a presser-bar having a longitudinal rib or projection, substantially as described, in combination with a carriage having a zigzag motion, as set forth. 120

3. The combination, with the carriage, of the reciprocating rack-bars for feeding the carriage forward, the arms which cause said rack-bars to reciprocate, the side racks, *B*, and pawls *e*, for holding the carriage against a 130 backward movement, and the cutting and compressing devices, substantially as described. 125

4. The combination of the carriage with the side racks, B, pawls e, for engaging in said racks, springs which act upon said pawls, and the right and left screws and nuts whereby the pawls can be disengaged from the racks, substantially as described.

In witness whereof I have hereunto set my

hand, this 8th day of August, A. D. 1882, at Chicago, Cook county, in the State of Illinois.

JAMES LORENZO GAGE.
